UNITED STATES PATENT OFFICE.

BEAT KUHNE, OF LEWISTOWN, MONTANA.

MILK-BOTTLE CAP.

Application filed March 10, 1926. Serial No. 93,729.

The present invention relates to improvements in closures for containers such as milk bottles and the like; and the primary object of the invention is to provide a novel 5 type of milk bottle cap embodying features whereby a portion of the cap may be swung outwardly of the remainder of the cap in a manner for providing an opening through which all or a portion of the contents of the 10 bottle may be poured or withdrawn.

A further object of the invention is to provide a milk bottle cap embodying a flat closure disc provided with a pull tab or flap having its free end portion extending from 15 the peripheral edge of the disc in a manner whereby the disc may be readily withdrawn from the mouth of the bottle without the requiring of a special instrument of any character being employed for removal of the cap 20 from the bottle.

A still further object of the invention is to so construct the cap as to permit of the cap being placed in position in the mouth of a milk bottle as by the standard capping 25 machines now in use.

A still further object of the invention is to provide a novel type of milk bottle cap embodying a tab so associated with the cap as to prevent possible separation of the tab 30 from the cap when a pull is exerted on the tab.

Other objects and advantages of the invention will be apparent during the course 35 of the following detail description, taken in connection with the accompanying drawing forming a part of this specification and in which drawing:

Figure 1 is a central vertical section 40 through the upper portion of a milk bottle and showing a cap constructed in accordance with my invention, in central section, and in a position for closing of the bottle.

Figure 2 is a view substantially similar 45 to Figure 1 but showing a portion of the cap swung upwardly to a position for providing an opening in the cap, and showing by way of example, a fragment of a straw or the like inserted through the opening in the cap for withdrawing of the contents of the 50 bottle.

Figure 3 is a top perspective view of the 55 improved cap as shown in Figures 1 and 2.

Figure 4 is a bottom perspective view of the same.

Figure 5 is an enlarged fragmentary section 55 on line 5—5 of Figure 3, and looking in the direction of the arrows.

Figure 6 is a bottom plan view of a slightly modified form of the invention, such type 60 being of a class whereby the whole closure disc will be withdrawn from the bottle upon the exerting of a pull upon the pull tab.

Figure 7 is an enlarged fragmentary section 65 on the line 7—7 of Figure 6.

Figure 8 is a still further slightly modified form of the invention, and showing the slits to each side of the pull tab extending from the top to the bottom surfaces of the closure disc.

In the drawing, and wherein similar reference characters designate corresponding parts throughout the several views, the letter A may designate a milk bottle of ordinary construction, and which bottles are provided at their upper ends with an inwardly 70 disposed annular seat or flange 10 and upon which the cap or closure is adapted to seat.

The cap as shown, and which may be formed of paper, pulp board, or any other desired material suitable for the purpose, 75 embodies a circular closure disc 12 and a pull tab or flap 13 by which the closure disc may be withdrawn from the mouth of the bottle A. The closure disc 12 has provided in its bottom side, a depression 14 80 having its side edges extending in diverting relation from the peripheral edge of the closure disc to a point relatively near the center of the disc. This depression 14 may either be formed by compressing a 85 portion of the closure disc, or if desired a portion of the disc may be cut out for providing the depression. Extending upwardly 90 through the closure disc, and along each of the inwardly diverging side walls formed by the depression 14, are slits or score lines 95 15 which extend throughout the entire length of the depression and terminate just below the top surface of the disc as is clearly illustrated in Figure 5. These inwardly 100 diverging slits 15 outline a lip 16 which is adapted to be swung upwardly from the peripheral edge of the disc and bend on the line 17 extending between the inner ends of 105 the slits. Thus it will be seen that the lip 16 is of less width at the periphery of the disc than at its inner end or bend line portion. By so having the slits or score lines

15 terminate slightly below the top surface of the disc, it will be seen that the closure disc will serve as an efficient sealing cap for the bottle, having no depressions or score 5 lines of any character provided on the top surface of the cap and into which foreign matter accumulates and consequently becomes mixed with the contents of the bottle when the lid is swung outwardly for 10 permitting of the contents being poured from the bottle. By so constructing the cap as to provide a perfectly smooth top surface, the top surface of the cap may be thoroughly cleaned before swinging of the 15 lip to provide an opening through which the contents of the bottle may be poured or withdrawn. It will be observed that the depression 14 is of substantially isosceles trapezoidal shape, having its base line of 20 least dimension disposed at the periphery of the closure disc.

Referring now to the pull tab or flap 13, and which may be formed of any suitable material impervious to moisture, such as 25 fiber board or the like, the same is of substantially triangular shape in plan, and of a thickness equal to the depth of the depression 14. This tab 13 is adapted to have its base portion 18 fit snugly within the depression 14 and be secured to the closure disc as by a suitable adhesive or as in the example shown as by a staple 19 which extends upwardly through the lip portion 16 of the closure disc. This staple is disposed 30 transversely of the base portion 18 and in parallel alignment with the bend line 17 of the lip. The tab 13 extends past the periphery of the closure disc as clearly illustrated in Figures 3 and 4, for providing a 35 grip portion 20 which when the closure disc is resting upon the seat 10 of the bottle A, will extend upwardly between the periphery of the closure disc and the neck portion of the bottle in a manner to be readily 40 grasped when desiring to raise the lip 16 for withdrawing of the contents of the bottle. 45

In operation, and referring particularly 50 to the form of invention as illustrated in Figures 1 to 5 inclusive, the grip portion 20 which extends upwardly past the top edge of the bottle, may be grasped between the thumb and forefinger and upon upward 55 drawing of the same, the uncut portions 22 disposed to each longitudinal side of the lip 16, will be severed thus allowing the lip to swing upwardly about the bend line 17 and providing an opening in the closure disc through which the contents of the bottle 60 may be poured, or into which opening a straw 50 may be inserted as shown in Figure 2. It will be observed that upon upward pulling of the tab, that a lateral strain 65 will be transmitted to the staple 19 and which lateral strain upon the staple

will prevent liability of the staple being withdrawn from the lip 15, and which withdrawal of the staple would be likely to happen were a direct pull exerted upon the staple.

With the form of invention as illustrated in Figures 6 and 7, and which form is intended for use when it is desired to withdraw the whole of the closure disc from the bottle, the same is provided with the usual depression in its bottom side but no cuts or score lines are formed in the disc to each side of the pull tab. Thus it will be seen that with this type, when a pull is exerted upon the tab 13 the whole portion of the closure disc adjacent the pull tab will be raised and not merely that portion lying above the base portion of the tab.

With reference to the form as shown in Figure 8, it will be observed that the slits 15' which are disposed at each longitudinal edge of the depression 14, extend clear through the closure disc in upwardly converging relation to one another. By so having the slits 15' extend upwardly in converging relation to one another, it will be seen that when the closure disc is positioned in the mouth of the bottle, that a substantially dove-tail fit will be provided at the side edges of the lip 16 and thus prevent ready upward swinging of the lip due to the wedging action formed by the inclined slits. The lip will be prevented from being forced inwardly by reason of the base portion 18 of the tab seating at its outer portion upon the seat 10 of the bottle. It is preferred that a coating of paraffin be placed upon the cap for sealing the upper and lower ends of the slit 15'.

By so having the slits extend inwardly from the periphery of the closure disc in diverging relation to one another, it will be observed that the grip portion 20 of the tab need not be of a width to prevent proper positioning of the disc upon the seat 10, and that a substantial portion of the lip 16 remains integral with the main body portion of the closure disc along the bending line 17 for preventing possible tearing or severing of the lip from the remainder of the disc when removing the closure disc in its entirety from the bottle.

It will readily be apparent that the object in so forming a depression in the bottom portion of the closure disc for receiving the tab 13, permits of an even or smooth bottom surface being provided for flush seating upon the seat 10 of the bottle.

From the foregoing description it will be apparent that a novel cap for milk bottles has been provided embodying a closure disc having a tab portion so disposed and connected thereto as to prevent possible severing of a lip portion of the closure disc from the main body portion thereof when a pull

is exerted on the tab for partially or fully removing the closure disc from the milk bottle.

Changes in detail may be made to the forms of the invention herein shown and described, without departing from the spirit of the invention or the scope of the following claims.

I claim:

10 1. A bottle cap comprising a closure disc having score lines provided at its under side and extending in diverging relation from the periphery of the disc, and a triangular shaped tab secured by its base portion to the 15 under side of the disc between said score lines at a point spaced a substantial distance inwardly from the peripheral edge of the disc.

2. A bottle cap comprising a closure disc 20 provided at its under side with a depression having its side edges extending in diverging relation from the periphery of the disc and having score lines extending upwardly in the disc at each side edge of the depression, and a triangular shaped tab fitting in 25 the depression and secured to the closure disc.

3. A bottle cap comprising a closure disc having a depression of substantially isosceles

20 trapezoidal shape in plan provided in its under side and having the base portion of least dimension disposed at the periphery of the disc, and a tab of substantially triangular shape having its base portion fitting in the depression and secured to the disc by 25 a staple extending in parallel relation with the inner larger end of the depression.

4. A bottle cap comprising a closure disc having a depression provided in its under side and score lines at each longitudinal 40 edge of the depression extending upwardly to a position relatively near the top surface of the disc, and a tab having a base portion of like configuration as that of said depression, fitting in the depression and secured to the closure disc and having a grip portion extending past the periphery of the disc.

5. A bottle cap comprising a closure disc 50 having a lip provided in the peripheral portion thereof by slits extending inwardly from the periphery of the disc in diverging relation to one another, and a tab secured to the underside of the lip at a point nearer the inner end of the lip and having a portion extending past the periphery of the disc.

BEAT KUHNE.
